(57) **CLAIM**

The ornamental design for a wall mounted distribution center, as shown and described.

DESCRIPTION

FIG. 1 is a perspective view of a new and ornamental design for a wall mounted distribution center;

FIG. 2 is a front view thereof;

FIG. 3 is a rear view thereof;

FIG. 4 is a left side view thereof;

FIG. 5 is a right side view thereof;

FIG. 6 is a top plan thereof; and

FIG. 7 is a bottom plan thereof.

FIG. 8 is a perspective view of a second embodiment of a wall mounted distribution center;

FIG. 9 is a front view thereof;

FIG. 10 is a rear view thereof;

FIG. 11 is a left side view thereof;

FIG. 12 is a right side view thereof;

FIG. 13 is a top plan thereof; and,

FIG. 14 is a bottom plan thereof.

The broken line portion of the figure drawings is included to show portions of the article that forms no part of the claimed design.

1 Claim, 14 Drawing Sheets
